UNITED STATES PATENT OFFICE

140,533

DESIGN FOR A BOLERO JACKET OR SIMILAR ARTICLE

Benjamin J. Schechter, Chicago, Ill.

Application December 16, 1944, Serial No. 116,941

Term of patent 7 years

(Cl. D3—4)

To all whom it may concern:

Be it known that I, Benjamin J. Schechter, a citizen of the United States, and a resident of the city of Chicago, county of Cook, and State of Illinois, have invented a new, original, and ornamental Design for a Bolero Jacket or Similar Article, of which the following is a specification, reference being had to the accompanying drawing, forming a part hereof.

Fig. 1 is a front elevational view of the bolero jacket or similar article showing my design; and Fig. 2 is a rear elevational view thereof.

I claim:

The ornamental design for a bolero jacket or similar article, as shown.

BENJAMIN J. SCHECHTER.
